CLAIM

I claim the ornamental design for a soft spatula tube applicator, as shown and described.

DESCRIPTION

FIG. 1 is a top perspective view of a soft spatula tube applicator showing my new design;

FIG. 2 is a top plan view thereof;

FIG. 3 is a right side view thereof, the left side being a mirror image thereof;

FIG. 4 is a rear view thereof; and,

FIG. 5 is a front view thereof.

1 Claim, 5 Drawing Sheets
